UNITED STATES PATENT OFFICE.

FREDERICK M. FURBER, OF HAVERHILL, MASSACHUSETTS.

SOLE-EDGE-TRIMMING TOOL.

SPECIFICATION forming part of Letters Patent No. 623,710, dated April 25, 1899.

Application filed October 26, 1898. Serial No. 694,615. (No model.)

To all whom it may concern:

Be it known that I, FREDERICK M. FURBER, of Haverhill, in the county of Essex and State of Massachusetts, have invented certain new 5 and useful Improvements in Sole-Edge-Trimming Tools, of which the following is a specification.

This invention relates to sole-edge-trimming tools in which a rotary cutter-head is 10 employed having teeth formed to act on the edge and portions of the top and bottom surfaces of a boot or shoe sole to simultaneously trim said portions and yieldingly-pressed buffering or rubbing blades which 15 project between the teeth of the cutter and are adapted to act on the trimmed surface formed on the bottom or outer face of the sole by the rotary cutter.

The invention has for its object to provide 20 a tool of this class in which the buffer-blades shall be free to move in and out without frictional resistance, and thus conform to the thickness of the sole.

The invention also has for its object to provide 25 a simple and effective means for adjusting the buffer-blades.

To these ends the invention consists in the improvements which I will now proceed to describe and claim.

30 Of the accompanying drawings, forming a part of this specification, Figure 1 represents a front elevation of a sole-edge-trimming appliance embodying my invention. Fig. 2 represents a section on line 2 2 of Fig. 1.

35 The same letters and numerals of reference indicate the same parts in both figures.

In the drawings, *a* represents a rotary shaft mounted in a suitable bearing *b*.

c represents the hub of a rotary cutter, 40 which is mounted on the reduced outer portion of the shaft *a* and secured thereto by a screw *d*, said hub being provided with blades *e'*, each of which has three cutting edges or portions 2, 3, and 4, arranged in the usual 45 manner for simultaneous action on the edge and on the adjacent portions of the top and bottom surfaces of a sole.

e represents a collar which is formed to closely fit the shaft *a* and is provided with 50 suitable means for attachment thereto, such as a set-screw *f*. To the collar *e*, at or near one end thereof, is joined a shield or guard

e², the collar and shield being preferably cast in one piece. The shield or guard projects from the point where it is joined to the collar *e* toward the opposite end of said collar and is preferably flared outwardly, so that its outer end, which is open, is of considerably larger diameter than its inner end. The shield or guard *e²* is separated from the portion of the collar *e* over which it projects by 55 an annular chamber *g*.

h represents a sleeve which is fitted to slide upon the collar *e* within the annular chamber *g*, said sleeve being normally pressed toward the open end of the chamber *g* by means of a spring *i*. The outward movement of the sleeve *h* is limited by means of complementary 65 stop members *j* and *j'* on the sleeve and collar. One of these members may be a shoulder formed by cutting a peripheral groove in the collar, while the other may be a screw inserted in the sleeve, as shown in Fig. 2.

To the outer portion of the sleeve *h* are affixed a series of buffer-blades *k*, which are 75 formed and arranged to project through the open end of the chamber *g* into spaces between teeth of the rotary cutter. If desired, there may be as many blades *k* as there are teeth *c'*, so that each space between the teeth 80 will receive a blade *k*, or the number of blades may be less than the number of teeth and spaces.

It will be seen that when the cutter is in operation the blades *k* are pressed yieldingly 85 against the bottom surface of the sole and act to smooth the face formed by the portions 4 of the cutting edges of the teeth *c'*.

The collar *e*, shield or guard *e²*, sleeve *h*, and blade *k* constitute an attachment which 90 is adapted to be applied and removed as a whole, the shield protecting the hands of the workman from injury by the blades. If desired, the shield may be provided with orifices *e³* *e⁴* for the circulation of air and for the escape of chips and cuttings which may find 95 their way into the chamber *g*.

Heretofore in devices of this character the shield or guard has been rigidly secured to the buffer-blades, so that the friction caused 100 by the rapid rotation of the device and the contact of the operator's hand with the shield causes the buffer-blades to come in contact with the cutter-blades and bind against the

same, so that their inward and outward movement is considerably impeded by friction. My improved construction above described overcomes this objection and makes the 5 buffer-blades very sensitive, so that they readily conform to the thickness of the sole whatever the thickness may be. The collar *e* may be readily adjusted in the shaft by loosening the set-screw *f*, thus permitting any desired 10 adjustment of the buffer-blades.

I claim—

1. A sole-edge-trimming appliance comprising a cutter-shaft, a cutter thereon, a shield having an open end adjacent to the cutter, said shield forming a chamber surrounding the shaft, and a series of spring-pressed buffer-blades movable in said chamber and normally projecting therefrom between the teeth of the cutter.
2. A sole-edge-trimming appliance comprising a cutter-shaft, a cutter thereon, a shield adjustably mounted on the shaft and having an open end adjacent to the cutter, said shield forming a chamber surrounding the shaft, a series of spring-pressed buffer-blades movable in the chamber, and means 25 for positively securing the shield to the shaft

in different positions and thereby adjusting the buffer-blades.

3. The improved sole-edge-trimming-tool 30 attachment hereinbefore described, the same comprising a collar having means for attachment to a cutter-shaft, a shield or guard joined to the collar at or near one end thereof and projecting toward the other end, said 35 guard being separated from the portion of the collar over which it projects by an annular chamber which is open at one end, a sleeve adapted to slide on the collar in said chamber and provided with a series of blades which 40 project from the open end of the chamber and are arranged to enter the spaces between the teeth of an edge-trimming cutter on said shaft, a spring in said chamber adapted to press the sleeve and its blades outwardly, and 45 stop members on the collar and sleeve, whereby the outward movement of the sleeve is limited.

In testimony whereof I have affixed my signature in presence of two witnesses.

FREDERICK M. FURBER.
